UNITED STATES PATENT OFFICE.

FRED J. MILLER AND ARTHUR H. MILLER, OF SILVER CITY, IOWA.

GUN-SHIELD.

1,320,888.

Specification of Letters Patent.

Patented Nov. 4, 1919.

Application filed September 18, 1918. Serial No. 254,691.

To all whom it may concern:

Be it known that we, FRED J. MILLER and ARTHUR H. MILLER, citizens of the United States, residing at Silver City, in the county of Mills and State of Iowa, have invented new and useful Improvements in Gun-Shields, of which the following is a specification.

This invention has reference generally to 10 improvements in that class of inventions known as fire arms and more particularly relates to a gun shield.

The invention has for its principal aim and object to provide a device of the above 15 mentioned character designed to be fastened on the rifle barrel in advance of the stock and capable of being raised to enable the soldier to shoot from a position within the trench or else lowered into close relation 20 with the barrel when a charge is being made and serves in both instances to protect the head of the soldier by deflecting the course of bullets.

More particularly this invention consists 25 in the provision of a device of the above mentioned character wherein all of the component parts are so constructed and related that the entire device may be readily and quickly attached in position on the barrel 30 of a conventional type of rifle.

It is a more specific object of this invention to provide a device of the above mentioned character wherein the body proper is of novel construction; to provide improved 35 means for attaching the body in position; and to provide coöperative means on the attaching support and the body of the shield for maintaining the body of the shield in either a raised or lowered position.

Among the other aims and objects of this 40 invention may be recited the provision of a device of the character described with a view to compactness, and in which the number of parts are few, the construction simple 45 and the cost of production low and the efficiency high.

Other improvements and novel details in the construction and arrangement of the various parts of the apparatus will be 50 brought out more in detail in the description to follow, which for a clear understanding of the invention should be considered in connection with the accompanying drawings forming a part hereof, and wherein 55 is disclosed for the purpose of illustration a convenient and satisfactory embodiment of

the invention. It is to be noted in this connection that minor changes in the construction and arrangement of parts may be made without departing from the principle of 60 operation of the various parts.

The invention is clearly illustrated in the accompanying drawings, in which:

Figure 1 is a side elevation of the device. 65

Fig. 2 is a longitudinal section thereof.

Fig. 3 is a cross section taken on line 3—3 of Fig. 1.

Fig. 4 is a perspective detail of the body of the shield.

Fig. 5 is a perspective detail of the attaching band or support. 70

Similar characters of reference are employed in all of the above described views, to indicate corresponding parts.

Referring now, more particularly, to the 75 accompanying drawings, there is provided a gun or rifle including a barrel 1 to which is attached the improved shield indicated in its entirety by the numeral 2.

In the present instance the shield comprises an attaching band 3 for disposition about the rifle barrel, the ends of the band terminating in spaced upright ears 4 for receiving a bolt 5 the threaded projecting terminal of which is engaged by a wing nut 85 6 which serves to clamp the band in position. 80

The shield proper consists of a body 7 formed of suitable metal and of a substantially semi-conical configuration at the apex 90 of which are formed spaced ears 8 designed to be pivotally arranged about the bolt 5, and the body is also formed in proximity to the ears with a sight opening 9 through which the sight on the gun is visible. 95

As intimated, suitable means have been provided for releasably holding the body in a raised position or in a lowered position in close relation to the barrel and in reducing this feature of the invention to practice 100 the body is provided on opposite sides with opposed arcuate slots 10 and also with opposed pairs of spaced openings 11 and 12 which are in circumferential alinement with the inner edge of the slots 10 and positioned 105 between these slots 10 and the opening 9. A pair of leaf spring members 13 are employed and have their inner terminals secured by suitable fasteners 14 to the inner faces of the ears 4. Push buttons 15 are carried by the outer terminals of the spring members 13 and project in opposite direction 110

and operate in the slots 10 while catches 16 also project from the outer faces and in opposite directions from the spring members 13 and are designed to be engaged with the 5 openings 11 for releasably locking the body in a raised position or engage with the openings 12 for releasably locking the body 7 in a closed position. The spring members 13 are shaped so as to normally lie in close re- 10 lation with the inner surface of the body yet are easily moved inwardly upon pressing the push buttons 15 to assure of the removal of the catches 16 from either of the openings 11 and 12 to permit the swinging of the 15 body whereupon, owing to the inherent resiliency of these members, the catches will engage the other openings 12, as is apparent.

It is believed in view of the foregoing description that a further detailed description 20 of the operation of the invention is entirely unnecessary. Likewise it is believed that the advantages of the invention will also be readily apparent.

What is claimed as new is:

25 1. A gun shield of the character described including an annular attaching band formed with spaced ears at its terminals, a bolt engaged in the terminals, a wing nut engageable with the bolt for clamping the band 30 in position, a semi-conical body having its apex pivotally arranged about the bolt and formed near its apex with a sight opening,

the body being also provided with opposed arcuate slots in its sides and also formed with openings between the slots and the 35 sight opening, spring members connected to the ears on the band and positioned in yielding relation with the inner surface of the body, catches projecting from the spring members and engageable with either of the 40 last mentioned openings, and push buttons projecting from the spring members and operable in the slots in the body for removing the catches from engagement with the 45 openings in the shield to permit of swinging of the shield to either a raised or lowered position.

2. A device of the character described including a shield pivotally mounted at one end, the shield being formed with arcuate 50 slots on opposite sides and with openings between the said slots and the pivot point, laterally yieldable spring members provided with catches engageable with the said openings, and push buttons carried by the spring 55 members and passing through said arcuate slots, whereby the shield may be caused to assume different positions on the pivot in the manner and for the purpose specified.

In testimony whereof we affix our signatures.

FRED J. MILLER.
ARTHUR H. MILLER.
